UNITED STATES PATENT OFFICE.

MARION MONROE GREEN, OF COUNTY LINE, TENNESSEE.

COMBINATION-TOOL.

SPECIFICATION forming part of Letters Patent No. 427,309, dated May 6, 1890.

Application filed January 13, 1890. Serial No. 336,832. (No model.)

To all whom it may concern:

Be it known that I, MARION MONROE GREEN, residing at County Line, in the county of Moore and State of Tennessee, have invented 5 a new and Improved Combination-Tool, of which the following is a specification.

My invention relates to that class of tools where a single instrument is provided with a number of parts formed and combined together to produce a series of tools most commonly used by mechanics and farmers.

To this end my invention consists in the peculiar arrangement and novel combination of parts comprising this tool, which will hereinafter be fully described in the annexed specification and particularly pointed out in the claims, reference being had to the accompanying drawings, in which—

Figure 1 is a side view of my improved 20 tool. Fig. 2 is an edge view; and Fig. 3 is a vertical central section on the line 3 3, Fig. 2.

In the accompanying drawings, A A' indicate two lever-arms, pivoted together at a by means of a removable pivot b, the outer face 25 of which is provided with a notch b^x, which forms a convenient saw-set, the outer ends of said arms forming the grip-jaws A² A³, while their inner ends form the handle-bars A⁴ A⁵, as shown, said arms being made of any desired length. The central or pivotal portion 30 of the arms, which are joined in the same manner as the ordinary scissors or hand-punch, are provided with radial recesses f f, arranged diagonally to the longitudinal axis of the central pivot, said recess adapted to 35 register when the arms A A' are opened outward slightly, whereby said aligning recesses f may be quickly slipped onto a wire, the meeting edges of said recesses forming shear-like edges adapted to cut the wire when said arms A A' are compressed, the said recesses f f passing out of alignment when the arms are closed in, as shown in Fig. 2.

The inner face of the upper ends of the 45 arm A' is provided with a projecting pin c, which fits a socket c' in the arm A, whereby a suitable leather-punch is provided. The outer face of the upper end of the arm A is formed with a suitable hammer-butt C, while 50 the opposite arm is provided with a nail-extracting claw D. Between the hammer and claw portion and the pivotal point the meet-

ing faces of the arms are formed into grippers for horseshoeing, (see k,) the lower end of said meeting faces being formed with recessed portions E, having serrated faces, forming a suitable means for adapting the tool for a pipe-wrench, said intermediate portion of the arms being extended laterally, as at E', to form an additional grip-section for the wrench 60 part. Below the pivot-point the arms are formed with adjacent beveled cutting-edges, forming a suitable pipe-cutter G, while the lower ends of the arms are provided with lateral hook-like fingers h h, especially adapted 65 to mend swag-wire by cutting in two and twisting together. The lower end of the arm A is provided with a tack-puller H, and the arm A' with a screw-driver J.

From the foregoing description, taken in 70 connection with the drawings, it will be observed that I form nine simple and commonly-used tools into one implement, such implement being more particularly adapted for use on farms where fences are used which are put 75 up by means of wire-connections. It will also be seen that my arrangement of the different parts of the tool is such that each tool may be used to special advantage, and that the construction thereof is such that the same 80 can be quickly, strongly, and cheaply made.

Having thus described my invention, what I claim, and desire to secure by Letters Patent, is—

1. A combination-tool formed of two arms 85 A A', pivoted together at a, said pivotal portions provided with wire-cutting recesses f f, the upper ends of the arm A provided with a nail-extractor, the arm A' with a hammer-butt, the meeting faces of said upper ends 90 A A' formed with a projection and a socket, respectively, whereby a leather-punch is provided, substantially as and for the purpose described.

2. An improved combination-tool consisting of two arms or levers A A', formed with pivotal portions, provided with wire-cutting recesses f f in the peripheral edges of said portions, said recesses disposed diagonally to the longitudinal axis of the pivot, the meeting faces of the upper ends of said arms provided with a leather-punch and with recessed portions forming a pipe-wrench, said arms provided with a pipe-cutter below its pivot, 95 100

the lower ends provided with wire-twisting hooks *h h*, one of said ends provided with a screw-driver, and the other with a tack-drawer, all arranged substantially as and for the purpose described.

3. The hereinbefore-described combination-tool, formed of two arms or levers *A A'*, pivoted at *a* upon a removable pivot *b*, the pivotal portions of said arms formed with wire-cutting recesses *f*, the upper ends of said arms formed with nipper-faces *k*, and a leather-punch above said upper faces, the arm *A* formed with a hammer *C*, the arm *A'* with a nail-extracting claw *D*, said meeting faces

formed into recesses *E* below the nipper part *15 k*, said recesses serving as a pipe-wrench, the meeting faces of said arms below their pivots formed with cutting-edges, serving as a pipe-cutter, the ends of the arms provided with hooks *h h*, one end of said arms formed into a screw-driver, and the end of the opposite arm formed into a tack-puller, all arranged substantially as and for the purpose described. 20

MARION MONROE GREEN.
